UNITED STATES PATENT OFFICE.

PATRICK H. LONERGAN, OF BOULDER, COLORADO.

RADIATOR CORE.

Application filed October 13, 1920. Serial No. 416,693.

To all whom it may concern:

Be it known that I, PATRICK H. LONERGAN, a citizen of the United States, residing at the city and county of Boulder and State of Colorado, have invented certain new and useful Improvements in Radiator Cores; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 The object of this invention is to provide a radiator core for internal combustion engines which has large water capacity and a long path of circulation, which is comparatively easy to build, and which is more 20 sturdy and durable than any type of radiator heretofore presented.

Briefly, the invention comprises a radiator which is built up of a plurality of transversely arranged superimposed sections or 25 tanks. Each tank has an inlet at the top adjacent one end and an outlet at the bottom adjacent the other end, whereby the circulation of the water through the core is through a long, tortuous or zigzag path. 30 Each section has front and rear walls, and the air tubes are passed through the section and the ends of the tubes fixed in said front and rear walls. Around the periphery of each section a plurality of contiguous air 35 cells is provided to assist the cooling.

In the drawings:

Fig. 1 is a front elevation.

Fig. 2 is a vertical cross-section on line 2-2 of Fig. 1.

40 Fig. 3 is a vertical transverse section through two sections or tanks, the cross-hatching being omitted to avoid confusion.

Fig. 4 is an enlarged cross-section through the sections of Fig. 3.

45 A complete radiator is shown in Fig. 1 which comprises a plurality of sections or tanks 10, which make up the core, an upper receiving tank 12, and a lower tank 14. Each of the sections or tanks 10 has there around 50 a plurality of contiguous air cells 15 made of thin metal, much after the fashion of cells of well-known types of radiators. These cells extend from front to rear of the core and assist the cooling. Each tank or section 55 10 has upper and lower walls 16 and front

and rear walls 18. The air cells 15 are connected with these tank walls in any suitable manner, such as by means of solder. The number of air cells secured to the sections is preferably as indicated in the drawings, that is, two rows of cells at the sides of the core and two rows of cells between adjacent sections. A plurality of air tubes 20 are passed through each tank and the ends of said tubes are secured in the front and rear walls or 60 plates 18 as by soldering. It will be seen from this that the water within each tank lies around the tubes 20 and is cooled by reason of the passage of air through said tubes 20. Cooling is further assisted by 70 means of the air cells 15, which carry away the heat radiated by the walls 16 and the end walls of the sections which extend vertically of the core. The inlet and outlet passages for the various sections are indicated 75 at 22, these openings being lined with sleeves 24 which are soldered or otherwise secured in position. It will be noted that the inlet opening for each section is at one end of the upper portion of the section, and that the 80 outlet opening is at the opposite end of the lower portion. With this construction the travel of the water is along a zigzag path from the upper receiving tank 12 through the sections 10 to the lower tank 14.

In building a radiator core, as many sections may be constructed, one upon another, as desired, in order to get the required capacity. It will be noted that the volume of water which may be contained 85 within the core is much larger than in present types of radiators, wherein the water circulates through small cells or small tubes. By reason of the fact that the water is positively conducted through a long path extremely efficient cooling results, and radiation of heat from the walls of each section is assisted by the passage of water through the air cells 15 so that the heat is readily absorbed. Another advantage of the device 90 is its comparative indestructibility, since it is much less affected by shocks and blows than any type of radiator heretofore known. Further than this, the radiator is not affected by freezing to as great an extent as in other types because of the fact that the tubes 20 will be compressed and yield instead of being expanded so that they would split. Even in the event one of the tubes should split or otherwise cause a leak, it can be temporarily 95 100 105 110

sealed by plugging the ends thereof with any available object, such as a piece of wood or cloth.

Demonstration shows that the amount of water required to replenish the supply within the core is very small. Because of the efficient cooling it has been found so far to be impossible to cause the radiator to boil.

- I claim:
- 10 1. A radiator core comprising a plurality of superimposed sections, each section having an inlet opening in its upper wall adjacent one end and an outlet opening in its lower wall adjacent the other end, and means in each section for cooling the contents thereof comprising a plurality of air tubes having their ends fixed in the front and rear walls of each section and extending through the section, and a plurality of cooling cells arranged along the periphery of each section.
  - 15 2. A radiator core comprising a plurality of superimposed sections, each section having an inlet opening in its upper wall adjacent one end and an outlet opening in its

lower wall adjacent the other end, and means in each section for cooling the contents thereof comprising a plurality of cooling cells arranged around the periphery thereof.

3. A radiator core-section comprising a tank having upper and lower walls, side walls, and front and rear walls, the upper wall having an inlet opening adjacent one end and the lower wall having an outlet opening adjacent the other end, and air tubes extending through the tank and having their ends fixed in the front and rear walls, there being a plurality of cooling cells arranged around the periphery of the section.

4. A radiator core-section comprising a tank, the upper portion having an inlet opening adjacent one end and the lower portion having an outlet opening adjacent the other end and a plurality of air cells contiguously arranged around the periphery of the section.

In testimony whereof I affix my signature.

PATRICK H. LONERGAN.
